COUPLING

Ben F. MacKeage, Jr., West Bridgewater, Pa.

Application November 30, 1946, Serial No. 713,266

5 Claims. (Cl. 287—1)

1

This invention relates to a coupling, and more specifically, to a coupling that is particularly useful for joining a propeller shaft to a drive shaft on ships and other craft.

An outstanding objection to most common types of marine couplings used on craft is that they are relatively complicated in construction and cumbersome; furthermore, many of these have the additional disadvantage that the driven or propeller shaft has radially extending parts integral therewith or bolted thereon, making it relatively difficult or impossible to dismantle these parts whenever it is necessary to make propeller shaft repairs, because in such instances, due to the close fit of the propeller shaft and encircling stationary tube or housing, it is necessary to dismantle any parts that project radially outwardly beyond the diameter of the propeller shaft.

An object of the present invention is to provide a relatively simple and inexpensive coupling especially useful in propeller drives for marine use in vessels and the like, and which is devoid of the above-mentioned disadvantages, inasmuch as it is of a design so that the propeller shaft can be readily slipped through the stationary tube which closely surrounds it so as to pull the propeller away from a ship without disconnecting any parts from the coupled end of the propeller shaft whenever repairs of the propeller are necessary.

A more specific object of this invention is to provide a novel coupling between a drive shaft and a driven shaft, which includes substantially a truncated hollow cone split in a longitudinal direction with keys between the two cone halves for keying the shafts together, which coupling members may be readily slipped into place or removed with a minimum effort and wherein the driven shaft has no radially extending parts extending from the coupling end thereof.

Other objects and advantages of the present invention will become apparent from a study of the following specification taken with the accompanying drawing wherein:

Fig. 1 is a plan view with parts shown broken away and in cross-section of a coupling embodying the principles of the present invention;

Fig. 2 is a cross-sectional view taken along line II—II of Fig. 1, and

Fig. 3 is an exploded view of the coupling shown in Figs. 1 and 2.

Referring more particularly to the figures, numeral 1 denotes a drive shaft which may be driven by a Diesel engine or any other source of motive power, which drive shaft has a ra-

dially extending flange 2. At the end of the drive shaft and centrally of flange 2 there is provided a seat or pocket 3 into which may be slipped or fitted the driven or propeller shaft 4 which may be connected to the propeller of a ship (not shown).

A ring 5 having a plurality of holes 6 disposed adjacent the periphery thereof encircles driven shaft 4 and is bolted to flange 2 by means of a plurality of bolts, such as 7, which extend through registering holes of ring 5 and flange 2. The internal bore of ring 5, instead of being cylindrical, is frusto-conical shaped so that there may be fitted snugly therein a pair of coupling elements 9 and 10 which comprise essentially a truncated hollow cone split in a longitudinal direction. More accurately speaking, however, elements 9 and 10, each have a perimeter which is slightly less than half the perimeter of a complete cone or circle by the amount indicated by the gap between these parts, shown more clearly in Fig. 3. The two gaps between elements 9 and 10 are completed or bridged by means of wedge-shaped keys 11 and 12 whose thickness added to the perimeter of elements 9 and 10 make up a complete truncated cone.

Radially extending grooves 13 and 14 are provided on diametrically opposite portions near the end of driven shaft 4, as shown more clearly in Fig. 3, into which may be slipped keys 11 and 12, as shown in dotted lines at the top of Fig. 3, for anchoring the straight side of wedges 11 and 12 to driven shaft 4. The tapered edges of keys 11 and 12 are fitted into grooves 15 and 16 of ring 5, and are thereby anchored thereto. The inner hollow cylindrical surface of elements 9 and 10 closely fit about an end portion 4a of reduced diameter of shaft 4, as shown more clearly in Fig. 1. The outer frusto-conical surfaces 40 thereof closely fit the corresponding surfaces of ring 5 so that, together with keys 11 and 12, elements 9 and 10 completely close the space between ring 5 and the portion 4a of reduced diameter. Hence it will be seen that there will be no voids in the coupling member and there will be a continuous bearing surface between the driving and driven parts of the coupling so as to transmit torques of substantial value.

Aside from the fact that the above-described coupling transmits relatively high torques, an outstanding feature of the coupling is that the driven or propeller shaft 4 has no radially outwardly extending parts formed thereon or otherwise fastened that would require an appreciable time period for uncoupling in the event that the

propeller secured to shaft 4 required repairs. As is well-known in propeller drives on ships and other craft, a conventional design is to provide a hollow stationary tube or housing closely fitted about the propeller shaft 4 which extends through a substantial portion of the length of the propeller shaft. Hence, when it is necessary to make repairs of a damaged propeller, it is required that the propeller shaft be uncoupled and pulled through the tube in the direction of the propeller, that is, towards the rear of the ship, so as to move the propeller away from the ship. Obviously, if radially extending parts are provided on shaft 4, this cannot be done, since such parts will interfere with the closely fitting stationary tube. However, in the coupling described herein, the propeller shaft 4 is of constant diameter throughout and has merely a portion of reduced diameter 4a so as to readily enable coupling or uncoupling whenever desired by placing or removing, respectively, elements 9 and 10 and keys 11 and 12, which involves a minimum of effort.

Thus it will be seen that I have provided an efficient, relatively simple and inexpensive coupling involving a minimum number of simple parts which enable the transmission of substantial torques and which coupling is particularly useful for coupling the drive shaft to the propeller shaft on a ship or other craft, although it should be understood that such coupling may be used for mechanical drives other than on ships and the like.

While I have illustrated and described certain specific embodiments of my invention, it will be understood that this is by way of illustration only and that various changes and modifications may be made within the contemplation of my invention and within the scope of the following claims.

I claim:

1. A coupling comprising a driving shaft and a driven shaft disposed in coaxial relationship, said driven shaft having a radial slot adjacent the end thereof, a wedge-shaped key fitted into said slot, a ring surrounding said slot and rigidly fastened to said driving shaft, said ring having a frusto-conical bore and a slot into which said key is fitted, and a longitudinally split, hollow, truncated cone fitted into said frusto-conical bore in said ring, the two halves of said cone being bridged by said key.

2. A coupling comprising a drive shaft having an end flange and a pocket formed centrally of said end flange, a driven shaft having an end fitted into said pocket, thereby positioning said shaft in coaxial relationship, a ring encircling said end of said driven shaft and being bolted to said flange, said ring having a frusto-conical bore and two diametrically opposite, radially extending grooves, said end of the driven shaft also having diametrically opposite, radially extending grooves, a pair of wedge-shaped keys having opposite edges thereof fitted into said two pairs of grooves for keying said driven shaft to said ring, and a pair of coupling elements filling the remaining space in said frusto-conical bore and between which said keys are sandwiched, each coupling element having a circumferential extent slightly less than half a circle by an amount equal to the thickness of one of said keys.

3. A coupling comprising a drive shaft having an end flange and a pocket formed centrally of said end flange, a driven shaft having an end fitted into said pocket, thereby positioning said shaft in coaxial relationship, a ring encircling said end of said driven shaft and being bolted to said flange, said ring having a frusto-conical bore and two diametrically opposite, radially extending grooves, said end of the driven shaft also having diametrically opposite, radially extending grooves, a pair of wedge-shaped keys having opposite edges thereof fitted into said two pairs of grooves for keying said driven shaft to said ring, and a pair of coupling elements filling the remaining space in said frusto-conical bore and between which said keys are sandwiched, each coupling element having a circumferential extent slightly less than half a circle by an amount equal to the thickness of one of said keys, said driven shaft having a cylindrical end portion of reduced diameter onto which said coupling elements are closely fitted.

4. A coupling comprising a drive shaft having an end flange, a driven shaft having an annular groove, a split ring formed of at least two sections receivable in said groove and interlocked with said driven shaft against axial movement thereon, said split ring providing a boss having a frusto-conical shape with its base in engagement with said flange, a coupling member having a frusto-conical bore bolted to said flange with the surface of said bore in engagement with the outer surface of said boss, the engagement of said boss with said flange and bore being effective to prevent axial movement of said boss with respect to said drive shaft, and keying elements cooperating with said boss and with said drive and driven shafts to provide an operative torque transmitting connection between said coupling member and said driven shaft whereby said shafts are constrained to rotate with each other.

5. A coupling comprising a drive shaft, a driven shaft having an annular groove, a split ring formed of at least two sections receivable in said groove and interlocked with said driven shaft against axial movement thereon, said split ring providing a boss projecting outwardly from the surface of said driven shaft, a coupling member connected to said drive shaft and engageable with said boss to prevent axial movement of said boss with respect to said drive shaft, and keying elements cooperating with said boss and with said drive and driven shafts to provide an operative torque transmitting connection between said coupling member and said driven shaft whereby said shafts are constrained to rotate with each other.
